UNITED STATES PATENT OFFICE.

ALBERT M. GUYTON, OF BROAD TOP, PENNSYLVANIA.

TOBACCO-BOX.

SPECIFICATION forming part of Letters Patent No. 324,105, dated August 11, 1885.

Application filed March 6, 1885. (Model.)

To all whom it may concern:

Be it known that I, ALBERT MARION GUYTON, of Broad Top city, in the county of Huntingdon and State of Pennsylvania, have invented a new and Improved Tobacco-Box, of which the following is a full, clear, and exact description.

The object of my invention is to provide a simple, inexpensive, and efficient box or case 10 wherein to hold a tobacco-plug and a knife to cut it, so that the tobacco may be kept moist and clean, and need not be bitten off by the user of it.

The invention consists in the peculiar construction and arrangement of parts, as hereinafter fully described, and pointed out in the claim.

Reference is to be had to the accompanying drawings, forming part of this specification, 20 in which similar letters of reference indicate corresponding parts in all the figures.

Figure 1 is a side elevation of my improved tobacco-box with its knife-pocket partly broken away. Fig. 2 is a side elevation of 25 the box, with the tobacco-plug and knife shown projected from the open top of the box; and Fig. 3 is a sectional plan view of the box, taken on the irregular line $\alpha\alpha$, Fig. 2.

The letter A indicates the tobacco-box, which 30 I make with the compartment B, for holding the plug C of tobacco, and the compartment or pocket D, for holding the knife, E, to be used in cutting the tobacco-plug into suitable pieces or shavings for consumption by chewing or smoking it.

At the top of the box is fitted a cover, F, which is hinged to the box at f, and has a suitable elastic catch, G, which presses against opposite side plates of the box when the cover 40 is closed to hold it shut.

Across the compartment B is fitted a slide, H, on which the plug C of tobacco rests, and which has a reduced end portion, which is adapted to slide in a slot, b, made through 45 one side of the box A, and in the pocket D is fitted the slide I, on which the point or end of the blade e of knife E rests, and the slide has a reduced portion or neck, which is adapted to move in a slot, d, made through the side 50 of the pocket D.

The slides H I have the attached knobs or

buttons h i, respectively, which may be pushed one way or the other to move the slides both ways along the box.

The operation is as follows: When the tobacco is to be used, the knob h of the slide H will be pushed outward toward the cover F by the thumb of the left hand, in which the box is held, and as the tobacco-plug C is forced outward it will strike the box-cover F and swing 60 it open, and the plug will be projected a suitable distance from the open end of the box. The thumb now will be transferred to the knob i of slide I, to push it forward or outward, to carry the handle of the knife E beyond the end of the box, when it may be removed from the pocket D by the right hand and used for cutting the tobacco, as may be required, and when the tobacco is cut the knife will again be placed in the pocket D 70 and pushed in, which carries the slide I back again to the bottom of the box, and the slide H will be moved back, to allow the tobacco C to re-enter the box, and the cover F may then be swung over and closed.

As the knife-blade e is not pivoted, but is rigidly fixed to and in line with the handle, the knife E is dangerous to carry uncovered in the pockets of clothing; hence the person using it to cut the tobacco will naturally replace it in the pocket D of box A, where it belongs; and by providing the knife with the box every necessary convenience is afforded for cutting the tobacco, so that it need not be bitten off for use, as often is done.

It is evident that my tobacco-box will be very useful to miners and others working in quite dark dirty places, and whose hands become very dirty and gritty, as the box-slides H I may easily be operated by their push-knobs h i, the one i moving only a sufficient distance in the short slot d to project the knife-handle sufficiently to take hold of it to draw it from the box; hence the knife will not be thrown from the box onto the dirty 90 ground or floor by the action of the slide. By moving slide H the end of the tobacco-plug may be projected sufficiently to allow a chew to be cut from it without handling the plug, and when in the box the plug is kept moist 95 and fresh and free from perspiration when carried in the pocket.

Having thus described my invention, what I claim as new, and desire to secure by Letters Patent, is—

A tobacco-box comprising a compartment, 5 B, for holding the tobacco-plug, and provided with a side slot, b, a compartment, D, for holding the knife E, and provided with a slot, d, slides H I, fitted, respectively, in compartments B D, and having neck portions passing

through the slots b d, and forming push-knobs to h i, for operating the slides, and a hinged cover, F, closing both compartments B D, substantially as herein set forth.

ALBERT M. GUYTON.
